US0D1011872S

(12) **United States Design Patent** (10) **Patent No.:** **US D1,011,872 S**
(45) **Date of Patent:** **** Jan. 23, 2024**

(54) **PACKAGE**

(71) Applicant: **BROTHER INDUSTRIES, LTD.**,
Nagoya (JP)

(72) Inventor: **Izumi Kato**, Nishio (JP)

(73) Assignee: **BROTHER INDUSTRIES, LTD.**,
Nagoya (JP)

(**) Term: **15 Years**

(21) Appl. No.: **29/749,965**

(22) Filed: **Sep. 10, 2020**

(30) **Foreign Application Priority Data**

Mar. 27, 2020 (JP) 2020-005943

(51) **LOC (14) Cl.** **09-03**

(52) **U.S. Cl.** **D9/415**

(57) **CLAIM**

The ornamental design for a package, as shown and described.

DESCRIPTION

FIG. 1 is a front elevational view of the package;
FIG. 2 is a rear elevational view thereof;
FIG. 3 is a left-side elevational view thereof, the right-side elevational view (not provided) being a mirror image of the left-side elevational view;
FIG. 4 is a top plan view thereof, the bottom plan view (not provided) being a mirror image of the top plan view; and,
FIG. 5 is a front elevational view thereof in an unfolded configuration.

The evenly spaced broken lines depict unclaimed parts of the package and form no part of the claimed design. The drawings are lined for the colors blue and black, in accordance with the symbol standards of MPEP § 608.02.

1 Claim, 5 Drawing Sheets
